SECTIONALLY COMPOSITE CERAMIC KILN

Saul Weingrad, New York, N. Y.

Application February 7, 1950, Serial No. 142,867

3 Claims. (Cl. 25—132)

1

This invention relates to a sectionally-composite ceramic kiln.

Most ceramic ware requires a preheating to a given temperature, firing at a high temperature, gradual reduction to an intermediate precooled temperature, and a final cooling to room temperature.

In one type of prior art kiln, which comprises a stationary ware-enclosing oven or furnace having door-controlled openings, the ware is, in a charging operation, moved after stacking from stacked position outside the kiln or furnace to an enclosed position within the kiln in which it is treated, and after treatment the ware is, in a discharging operation, again moved out of the kiln to its initial position where it is cooled to permit subsequent handling, the ware being usually initially stacked on movable conveying units that are moved with the stacked charge of ware into and out of the oven or furnace and both charging and discharging are done while the kiln is in cooled condition.

In another type of prior art kilns, known as "tunnel kiln," the kiln is also stationary and ware to be treated is usually stacked upon and conveyed in a continuously-moving operation by conveyors such as cars, moving belts, pushers or other conveying devices through a tunnel in said stationary kiln wherein the preheating and firing of the ware at the different temperatures required is accomplished by heating varying sections of the kiln at varying temperatures and by slowly moving the ware on such devices through such tunnels or passageways therein.

Tunnel kilns must necessarily be of considerable length with platforms, sidings and successively connected parts or sections heated to the varying degrees of temperature required for subjecting the ware during travel therethrough to each of the temperatures required to cause the necessary preheating, firing and precooling thereof. The movement on conveying devices through the kilns sometimes results in wrecks and breakage of the ware. This type of kiln is also geared to a given rate of travel of the ware and constant flow through the opening with a continuous operation of 24 hours in a day. Certain types require two men and all types require constant attendance and the use of considerable man power.

In both of these types of kilns, the ware is moved either during the heat treatment or before and after such treatment and in such movement is necessarily subjected to a certain degree of vibration or jostling.

One of the objects of my invention is to avoid

2

the movement of the charge of ware after the stacking thereof and with this end in view I provide a kiln including a stationary ware-supporting section on which the ware is stacked and on which, without further movement thereof, said ware is enclosed by a hood section to enable subjecting thereof to the necessary heat treatment, and to enable a batch or a series of batches of ceramic ware such as crockery to be stacked and to be economically subjected without movement to the required preheating, firing for maturing or fixing of decorations or pigments and precooling temperatures.

Another object of my invention is to accomplish the necessary operations hereinabove referred to in a relatively small area or space and with a greater economy in labor and other factors than it is possible to obtain for similar capacities or productions with prior art kilns, and to increase 20 the work area over the stationary oven type of kiln.

Another object of my invention is not only to avoid the travel or movement of the ware during treatment but to enable a high-heating of a batch or charge on one stationary section while another batch or charge on a second stationary section is being subjected to a preheating operation.

Another object of my invention is to provide a relatively short kiln of composite structure comprising a stationary charging and discharging kiln-section or ware-charging and discharging station adapted to form the floor section of my composite kiln and on which the ware is initially stacked in a suitable charge or batch combined with a hood-section comprising a relatively movable floorless member adapted to fit over and enclose said charging and discharging section, together with the batch of ware mounted thereon.

Still another object of my invention is to provide a sectional kiln construction which is adapted to effectively position and utilize electrical heating elements to enable the application of the heat required to treat a batch or charge of ware.

Still another object of my invention is in a kiln embodiment of the type specified to utilize tracks to enable facile movement of my movable hood-section, both in its movement toward and away from a single stationary ware-supporting section or cooperate successively with a plurality of stationary sections.

With these and other objects in view, the invention comprises the combination of members and arrangement of parts so combined as to coact and cooperate with each other in the performance of the functions and the accomplish-

ment of the results herein contemplated, and comprises in one of its adaptations the species or preferred form illustrated in the accompanying drawings, in which:

Fig. 1 is a view in side elevation of a composite kiln embodying my invention and having two stationary charging and discharging sections, each adapted to cooperate sequentially with two movable hood or housing sections comprising a firing section and a preheating-and-precooling section to treat charges or batches of ware;

Fig. 1A is a fragmentary view in side elevation similar to Fig. 1 showing one of the two stationary charging and discharging sections illustrated in said Figure 1 in cooperative relationship with a preheating-and-precooling section;

Fig. 2 is a section on the line 2—2 of Fig. 1 looking in the direction of the arrows;

Fig. 3 is a section on the line 3—3 of Fig. 1, looking in the direction of the arrows;

Fig. 4 is a section on the line 4—4 of Fig. 1A, looking in the direction of the arrows;

Fig. 5 is a fragmentary view in plan of the high heat housing shown in position over a charging section;

Fig. 6 is a section on the line 6—6 of Fig. 2, looking in the direction of the arrows;

Fig. 7 is a section on the line 7—7 of Fig. 1, looking in the direction of the arrows; and

Fig. 8 is a section on the line 8—8 of Fig. 1A, looking in the direction of the arrows.

Referring now to these drawings which illustrate a preferred embodiment of my invention, 1 indicates a base structure comprising a track having rails suitably elevated above a floor or other supporting surface 2. As shown, the supporting base structure 1 is preferably built of a pair of strong, rigid, parallel metallic beams having positioned between the same at least one stationary ware-supporting section or station 3 and being provided with tracks or rails on which is mounted at least one movable hood section 4 or 5 adapted to cooperate with said ware-supporting section 3. Preferably a plurality of such charging and discharging sections are employed and as illustrated in Fig. 1 two of these ware-supporting sections 3, 3^a are arranged on the base or supporting structure 1 in alignment with each other.

Each of these stationary ware-supporting sections is disposed in a horizontal plane and provided with a horizontal stacking surface preferably comprising a grill member on which a batch or charge of ceramic ware is adapted to be stacked for treatment and thereafter discharged. Each of such ware-supporting sections—together with the pile or stack of ware mounted thereon—is, in the heat treatment of said ware, adapted to be covered and completely enclosed by one or both of the movable hood sections 4 and 5 hereinafter more particularly described. Preferably each charge is enclosed successively or alternately by both hood sections 4 and 5, which are mounted on suitable wheels and comprise a preheating-and-precooling hood section 4 and a high-heat kiln section 5.

In accordance with my invention, each movable hood-section is caused to travel sequentially into a position over said ware-supporting section to form therewith a completely enclosed sectional kiln in which the stationary ware-supporting section forms the ware-supporting floor on which the charge of ware is suitably stacked within given limits fixed by the area of the hood sections and the hood section will provide walls for enclosing

at the sides, top and ends of the charge to confine the same and to permit the application to said charge of the heat required in the treatment of the ware.

As illustrated, the two ware-supporting sections 3, 3^a are identical in construction and each embodies a table 6 on which is preferably mounted a stacking grill 7 on which a charge or batch 8 of ware, represented in outline by the dot and dash lines in Figs. 1 and 3, is adapted to be stacked.

In the embodiment shown, a series of electrical heating elements 9 are preferably supported on the table 6 below the grill 7 and these heating elements 9 are, as shown, mounted in suitable grooves in a suitable bed of refractory insulating material 10.

In the preferred embodiment of my invention shown, a suitable charge of ware, the dimensions of which will, as aforesaid, be governed by the capacity of the hood section, is stacked on the grill 7 of a ware-supporting section and this ware will then first be subjected to a preheating operation. This preheating will preferably be accomplished by moving the preheating-and-precooling hood section 4 into the position over the charge-supporting section 3^a as shown in Fig. 1A. When the sections are thus in cooperative enclosing positions, energizing of the heating elements 9 will provide a certain low temperature sufficient for the purpose of preheating the charge 8 of ceramic ware or material.

An efficient preheating of the charge 8 of ceramic ware requires a complete enclosure of the ware and for this purpose the movable preheating-and-precooling hood-section is mounted on a suitable truck 11 which is floorless, and has at its lower end an opening 11^a that is adapted to fit the edges of the said ware-supporting section while the walls of said hood section enclose said charge or batch of ware. The truck 11 is mounted on four wheels and provided at opposite ends with opening and closure members which, as shown, each comprise double swinging doors 12 mounted on hinges 12^a and provided with latching and tightening elements 12^b. The preheating-and-precooling hood-section 4 preferably comprises a thin wall structure of metal, such as steel, and lined with asbestos or other heat insulating material and suitably reinforced. In positioning the section 4 one set of the double doors 12 thereof are opened, as shown in dot and dash lines in Fig. 1, and after the stacking of the charge on one of the stationary sections, said movable section 4 is caused to travel along the floor into position over said section 3^a so that when the door is closed, the two sections will form a composite kiln which will completely enclose the said charge 8 on all sides, including the front, back, top, bottom and sides thereof. Energizing of the heating elements on the ware-supporting section 3 will now enable a preheating of the charge 8. The floorless hood member 4 is a relatively thin-walled structure and relatively light so as to permit quick and ready movement, and, in the embodiment shown, is arranged to straddle and snugly fit over any one of the ware-supporting sections 3, 3^a and the roof portion is preferably provided with suitable vent openings 13. As illustrated, the walls of the hood section 4 are reinforced by angle-irons, and the lower ends of these angle irons are formed into feet and provided with rollers to permit ready movement of the section.

In the embodiment illustrated, the side edges

of the opening in the section 4 and the side edges of the section 3^a are provided with interengaging elements and, as shown, the side rails of the open lower end of the truck portion are provided with angle iron members having downwardly projecting flanges 14 adapted to fit into channel irons 15 on the side edges of the ware-supporting section, thus providing between the supporting section 3^a and said preheating-and-precooling section 4 a suitable joint preferably filled with sand to seal it and which will assist in preventing passage of heat in any serious amount out of the composite sectional kiln when so connected.

In Figs. 1, 4 and 8 I have shown a preheating-and-precooling section 4 cooperating with a ware-supporting section 3^a and when the electrical elements on the ware-supporting section shown are energized, a sufficient heat may be applied within the composite kiln so formed to produce what is known in the ceramic art as a preheating of the charge of ware.

Such a preheating structure, however, is not sufficient or efficient to enable the application to the ware of a firing, maturing or design-fixing temperature, and, therefore, after such a preheating operation is completed, I replace the hood section 4 with a movable high-heating hood-section 5. This movable high-heat hood section 5, as shown more particularly in Figs. 5, 6 and 7, has heating elements mounted on all its vertical walls including side walls and doors thereof to provide, in cooperation with the heating elements mounted in the horizontal surface of the stationary section, the required temperature for maturing or fixing the pigments or designs thereon. This section comprises a heavy steel-plate structure suitably reinforced and lined at sides, ends and roof by a layer or two layers of refractory fire-brick lining members. As shown, these fire-brick walls at both sides and ends are provided with grooves having inlaid within the same electrical heating elements 17. This high heat hood section 5 is extremely heavy, and in accordance with my invention, I mount the same upon heavy metal wheels to enable movement back and forth on tracks 18 mounted on the metallic superstructure 1. Tight joints preferably filled with sand are formed between the edges of the opening in the bottom of the hood section 5 and the stationary ware-supporting section received therein. As shown, the side walls 16^a, 16^b are supported at their lower ends on inverted channel members 19 having flanges fitting into the grooves formed by angle-irons on the section 3, the joint between the angular member and said channel iron being such as to prevent the passage of an appreciable quantity of heat therethrough. The lower surfaces of the doors at opposite ends of the hood section 5 are bevelled and close against similarly bevelled surfaces on the ware-supporting section 3 to provide a substantially tight enclosure of said section and the load or charge of ware supported thereon. In view of the large number of heating elements distributed on the surfaces of the vertical surfaces of the section 5, it will be apparent that a high heat may be procured when the multiple heating elements on the four vertical walls of the high heat hood section are positioned over the heating elements on the ware-supporting section to cause the charge or load of ware to be surrounded by heating elements at the bottom and four sides and also to be completely enclosed by heat-insulating walls.

The high-heat hood section 5 is, as shown, pro-

vided in its roof portion with pairs of flues or vents 19, 20 provided with regulating elements 19^a, 20^a. Said roof portion is composed of a double layer of refractory bricks, the outer layer being locked in place by bars 21 which pass through holes in an inner layer of bricks and are suitably connected at their outer ends to the metallic enclosing casing to securely maintain both layers of the ceiling bricks in place. It will be apparent that my movable high-heating hood section 5 may be used alone in cooperation with one of the stationary ware-supporting sections 3, 3^a to provide a complete treatment for a batch of ware, or that both hood sections 5 and 4 may be used in cooperation with the stationary ware-supporting sections 3 and 3^a for this purpose.

In one method of operation, ware may be stacked on the grill 7 of the ware-supporting section 3 to produce a charge of proper dimensions as shown in Fig. 1. The high-heating hood-section 5 carrying its multiplicity of heating elements may be moved on its wheels over the tracks into cooperating position to provide an enclosure for the charge of ware thereon, the electrical heating elements of the stationary ware-supporting section 3 may be utilized to procure a preheating temperature, and the heating elements of the high-heating hood-section may then be energized to provide by the heat of the combined elements of the ware-supporting section and of the high-heating hood-section a high temperature within said enclosure that will be capable of maturing the ware or fixing the pigments or decorations thereon. Such high temperature within the high-heat section and its duration may be also observed and determined by suitable conventional means and are also regulated by the vents 19, 20 and other conventional means. A reversal of this method will enable a precooling whereupon the high-heating hood section may be moved off the charge and the charge-supporting section to permit discharging of the ware.

In another method of operation, both hood sections 4 and 5 may be used conjointly. For example, during the high-heat treatment of the charge hereinabove described on section 3 in the high-heat hood-section 5, a charge on section 3^a may be enclosed by and preheated in the lighter preheating and precooling hood-section 4 by the use of the elements on the ware supporting section 3^a. When a proper preheating is accomplished, this lighter hood section 4 may be then removed and replaced by the high-heating section, and if desired, the said lighter hood section may be moved around to section 3 and utilized as a precooling enclosing hood-section therefor.

Having described my invention, I claim:

1. A sectionally composite kiln embodying, in combination, a supporting surface, a plurality of sections mounted on said supporting surface and comprising a stationary floor section of given dimensions raised above said supporting surface and provided with a stacking surface for a load of ware, a three dimensional movable hood section comprising a unitary straight-walled vehicle mounted at its lower edges on wheels and having at its bottom portion an opening communicating with a load-enclosing compartment within said vehicle, said vehicle being composed of a top portion, two straight side-wall portions formed integrally therewith and end wall portions carried by said side wall portions, at least one of said end wall portions comprising a door hingedly

mounted on a side wall portion to permit one end of said vehicle to be opened into communication with said bottom opening and load-enclosing compartment for the reception of a load of ware stacked on said stacking surface, said open bottom portion having dimensions substantially similar to the dimensions of said raised floor section, said hood section being movable edgewise of and across said raised floor section into substantial registration therewith to closely fit said open bottom portion and to provide a ware-supporting floor for said load-enclosing compartment, said hood and floor section, upon such movement into substantial registration and closing of said door, being adapted to completely enclose a stacked load of ware, and heating means on one of said hood and floor sections for heating ware within said load-enclosing compartment formed by said movable hood and stationary floor sections.

2. A sectionally composite kiln as claimed in claim 1 in which the hood section is composed of heat-insulated walls and carries on its side walls electrical heating elements to surround a load of ware on said stationary floor section.

3. A sectionally composite kiln embodying, in combination, a supporting surface, a stationary floor section of given dimensions raised above said supporting surface and provided with a stacking surface for a load of ware, a three dimensional movable hood section comprising a unitary straight-walled vehicle mounted at its lower edges on wheels and having at its bottom portion an opening communicating with a load-enclosing compartment within said vehicle, said vehicle being composed of a top portion, two straight side-wall portions formed integrally therewith and end wall portions carried by said side wall portions, at least one of said end wall portions comprising a door hingedly mounted on

5 a side wall portion to permit one end of said vehicle to be opened into communication with said bottom opening and load-enclosing compartment for the reception of a load of ware stacked on said stacking surface, said open bottom portion having dimensions substantially similar to the dimensions of said raised floor section, said hood section being movable edgewise of and across said raised floor section into substantial registration therewith to closely fit said open bottom portion and to provide a ware-supporting floor for said load-enclosing compartment, said hood and floor section, upon such movement into substantial registration and closing of said door, being adapted to completely enclose a stacked load of ware, said load-enclosing compartment being lined with heat-insulation material and the stationary platform section and movable hood section each being provided with 10 independent heating elements to permit initial preheating and subsequent high heating of a charge of ware on the stationary platform section.
